US00D722882S

(12) **United States Design Patent**
Castillo Higareda et al.

(10) **Patent No.:** **US D722,882 S**
(b4) **Date of Patent:** **** Feb. 24, 2015**

(54) **BOTTLE**

(75) Inventors: **Jose de Jesus Castillo Higareda**, Racine, WI (US); **Peter M. Neuman**, Racine, WI (US); **Holger Hampf**, Munich (DE); **Matthew D. Hern**, Malibu, CA (US); **Gary B. Swetish**, Racine, WI (US); **Benjamin R. Lloyd**, Milwaukee, WI (US)

(73) Assignee: **S.C. Johnson & Son, Inc.**, Racine, WI (US)

(**) Term: **14 Years**

(21) Appl. No.: **29/412,300**

(22) Filed: **Feb. 1, 2012**

Related U.S. Application Data

(63) Continuation-in-part of application No. 29/380,459, filed on Dec. 6, 2010.

(57) **CLAIM**

The ornamental design for a bottle, as shown and described.

DESCRIPTION

FIG. 1 is a top perspective view of a bottle showing our new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The broken lines appearing in FIGS. 1-7 define the bounds of the claimed design and/or disclose environment related to the claimed design, and therefore form no part of the claimed design.

1 Claim, 6 Drawing Sheets
